UNITED STATES PATENT OFFICE

166,786

COMBINATION TELEVISION AND RADIO- PHONOGRAPH CABINET

Samuel E. Adler, Chicago, Ill., assignor to Admiral Corporation, Chicago, Ill., a corporation of Delaware

Application January 19, 1952, Serial No. 18,115

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combination Television and Radio-Phonograph Cabinet, of which the following is a specification, reference being had to the accompanying drawings, forming a part hereof.

Fig. 1 is a front perspective view of a combination television and radio-phonograph cabinet the doors of which are open, showing my new design;

Fig. 2 is a front elevational view of the same, the doors being closed; and

Fig. 3 is an elevational view of the right side of the cabinet, a portion thereof being broken away.

The dominant features of my design reside in the portions shown by full lines of the drawings.

The left side of the cabinet resembles the right side, and the back is plain.

I claim:

The ornamental design for a combination television and radio-phonograph cabinet, as shown and described.

SAMUEL E. ADLER.
